[57] CLAIM

The ornamental design for bathtub shower splash guard, as shown and described.

DESCRIPTION

FIG. 1 is a right side elevational view of a bathtub shower splash guard showing my new design;

FIG. 2 is a front elevational view thereof;

FIG. 3 is a left side elevational view thereof;

FIG. 4 is a bottom plan view thereof;

FIG. 5 is a rear elevational view thereof; and,

FIG. 6 is a top plan view thereof.

It is to be understood that the center of FIG. 5 is broken away for convenience of illustration.

FIG. 1

FIG. 2

FIG. 3

FIG. 4

FIG. 5

FIG. 6
